UNITED STATES PATENT OFFICE.

ALBERT E. COLE, OF LONDON, ENGLAND.

HINGE FOR CLOSED BODIES OF MOTOR-CARS AND THE LIKE.

1,377,058.

Specification of Letters Patent.

Patented May 3, 1921.

Application filed November 13, 1919. Serial No. 337,817.

To all whom it may concern:

Be it known that I, ALBERT EDWARD COLE, subject of the King of Great Britain, residing at 235 Hammersmith Road, London, 5 W. 6, England, have invented certain new and useful Improvements in Hinges for Closed Bodies of Motor-Cars and the like, of which the following is a specification.

This invention relates to hinges for closed 10 bodies of motor-cars and the like, particularly to bodies of the coupé or cabriolet types, and has for its object to provide an improved construction of double hinge which is adapted to be fitted at the junction of 15 the front cant rail, back cant rail and center pillar so that all three members can be lowered.

A hinge constructed in accordance with 20 this invention comprises a substantially inverted L-shaped member, fitted at the upper extremity of the center pillar, a plate fitted to the front extremity of the back cant rail and pivotally connected at one end to the heel of the L-shaped member and at its 25 other end to a straight member which is fitted to the rear extremity of the front cant rail, and, a link connecting the straight member near its pivoted end to the toe of the L-shaped member.

30 The L-shaped member and straight member are preferably formed of channel section and the link and plate may be formed with one or more strengthening ribs.

In order that the invention may be fully 35 understood, it will now be described with reference to the accompanying drawings in which Figure 1 is a side elevation showing one form of hinge fitted in position and Figs. 2 and 3 are views showing the front 40 and back of the hinge respectively.

The hinge comprises the substantially inverted L-shaped member *a* which is formed of metal of channel section as shown at *b* and *c*. Pivoted at *d* is a plate *e* which is 45 itself pivoted at *f* to the straight member *g*. The said member *g* is connected to the toe *l* of the L-shaped member *a* by the link *h* which is pivoted thereto by the pivots *j* and *k*. The link *h* is formed with a central rib 50 *m* and the plate *e* is formed with ribs *n*, *n* for strengthening same.

The member *g* is also formed of channel section as shown at *o*.

The member *a* is fitted by screws or the like to the center pillar *p*; the plate *e* is 55 fitted to the back cant rail *q* and the member *g* is fitted to the front cant rail *r*.

The dotted lines in Fig. 1 show the position of the hinge when the hood is lowered and where it will be seen that the center 60 pillar *p* and back cant rail *q* form, combined, one straight member and the front cant rail *r* is rotated about its pivot *f* until it rests on the back cant rail *q*.

The center pillar *p* is hinged at *s* to the 65 car body *w* and the back cant rail *g* is hinged at *t* to the back pillar *u* which is itself connected to the body *w* by the hinge *v*. The hinges *s*, *t* and *v* are of the usual pattern.

70 A hinge constructed in accordance with this invention is very light in weight and is very strong.

What I claim is:—

1. A hinge for closed bodies of motor cars 75 and the like comprising a substantially inverted L-shaped member, adapted to be fitted to the upper extremity of the center pillar; a plate, fitted to the front extremity of the back cant rail and pivotally connected at one end to the heel of the said L-shaped member and at its other end to a straight member which is fitted to the rear extremity of the front cant rail and a link 80 connecting the straight member near its pivoted end to the toe of the L-shaped member.

2. A hinge for closed bodies of motor cars and the like comprising a substantially inverted L-shaped member attached to the upper end of the center pillar, a plate attached to the front extremity of the back cant rail, an element attached to the rear extremity of the front cant rail, said member and element being pivotally connected to 90 said plate at spaced points and a link connecting said element to the toe of said L-shaped member.

In testimony whereof I have hereunto set my hand in presence of two subscribing 100 witnesses.

ALBERT E. COLE.
